CLAIM

The ornamental design for a side saddle merchandiser, as shown and described.

DESCRIPTION

FIG. 1 is a perspective view of a side saddle merchandiser showing our new design, with environmental structure shown in broken lines for purposes of illustration only and forming no part of the claimed design;

FIG. 2 is a front elevational view thereof, the rear elevational view being a mirror image thereof;

FIG. 3 is a side elevational view thereof, the opposite side being a mirror image thereof;

FIG. 4 is a top plan view thereof; and,

FIG. 5 is a bottom plan view thereof.
